UNITED STATES PATENT OFFICE.

JACOB B. PERKINS, OF FRANKLIN, ILLINOIS.

COAL ATOMIZER.

Application filed October 8, 1923. Serial No. 687,294.

To all whom it may concern:

Be it known that I, JACOB B. PERKINS, a citizen of the United States, residing at Franklin, in the county of Morgan and

5 State of Illinois, have invented certain new and useful Improvements in Coal Atomizers, of which the following is a specification, reference being had to the accompanying drawings.

10 This invention relates to improvements in coal atomizers and has for an important object thereof the provision of a device for producing finely pulverized or atomized coal.

15 An important object of the invention is to provide a device of this character which is simple in its construction and operation and in which means are provided for pneumatically removing the atomized coal.

20 A further object of the invention is to provide in a device of this character a novel and improved screening device for insuring reduction of the delivered coal to a predetermined size, all coal above this size being returned to the machine for further 25 pulverization.

25 A still further object of the invention is to provide a device of this character in which the parts are ready of access and 30 which may be readily cleansed in event of clogging thereof.

35 These and other objects I attain by the construction shown in the accompanying drawings wherein for the purpose of illustration is shown a preferred embodiment of my invention and wherein:-

40 Figure 1 is a side elevation partially in section of coal atomizing apparatus constructed in accordance with my invention;

45 Figure 2 is a rear end elevation of the drum;

Figure 3 is a fragmentary perspective of the rotary element within the drum;

50 Figure 4 is a section on the line 4-4 of Figure 1;

Figure 5 is a section on the line 5-5 of Figure 1;

Figure 6 is a section on the line 6-6 of Figure 5; and

55 Figure 7 is an enlarged sectional view on the line 7-7 of Figure 2.

Referring now more particularly to the drawings, the numeral 10 designates a drum or cylinder, having front and back ends

60 11 and 12, which is provided with hinged doors 13 affording access to the interior

thereof. The drum is preferably mounted upon a solid base 14 and is provided at diametrically opposed points upon its periphery with flanges 15 by means of which it 60 may be secured to the base.

Disposed within the drum is a shaft 16 which is coaxial with the drum and has its end portions rotatably mounted in bearings 17 formed in the ends 11 and 12. Ad- 65 jacent its ends interiorly of the drum the shaft has secured thereto spiders 18 each consisting of a central or hub portion from which extend outwardly arcuately curved arms 19, all of the arms 19 being curved in 70 the same direction and as will appear from an inspection of Figure 4, in which the arrow indicates the direction of rotation, curved against such direction of rotation. Pivoted to the free ends of the arms 19 75

to swing in the plane of rotation of the arms are roller mounts 20 in which are rotatably mounted the pivots of rollers 21 which rollers are preferably constructed of hard steel. To the arms 19 upon the outer 80 surface thereof or that surface which during the rotation of the spiders 18 opposes

the interior surface of the drum is secured an angle iron 22, one flange of which is rigidly secured to the arm and the other 85 flange of which is directed radially toward the wall of the drum. It will be noted that

the curvature of the arms permits the rollers 21 to be dragged after the arms where they will exercise less tendency when encountering obstructions to place a breaking strain upon the arms and at the same time the curvature of the arms provide a 90 convenient seat for the scraper flange produced by the radially directed flange of 95

the angle iron 22. These scraper flanges will have their outer edge portions spaced from the inner wall of the drum a short distance so that they will at all times leave 100 upon the wall of the drum a thin coating of coal to be acted upon by the rollers 21.

There is further mounted upon the shaft 16 midway its ends and preferably slightly nearer the rear end 12 a disk 23, the purpose of which will presently appear. One end of the shaft 16 has secured thereto 105 means, indicated in the present instance as a pulley 24, whereby power may be applied to rotate the shaft.

In the front end wall an opening is 110 formed with which communicates an inclined chute 25 leading from a hopper 26

- in which may be placed the coal to be reduced. The lower end of the hopper is preferably provided with an agitator 27. With the chute 25 adjacent the point of its communication with the drum a conduit 28 is in communication, this conduit leading from a blower 29, the blower 29 and agitator 27 being operated from any suitable and preferably from the same source.
- 10 Coal placed in the hopper 26 will be agitated and delivered into the conduit 25 where it will be gathered up by the blast from the blower 29 and blown into the drum 10. The disk 23 acts as a baffle within the drum checking the rush of air and causing the coal carried thereby to be dropped to the bottom of the drum where it will be acted upon by the rollers 21 and scrapers 22.
- 15 20 With the rear or outlet end 12 at the top thereof, a discharge conduit 30 is in communication. This conduit has arranged therein at spaced intervals a plurality of screening devices 31, 32 and 33 which are graduated as to their screening qualities, the screen 31 next adjacent the drum being the coarser, the next being finer and the screen 33 being the finest. The discharge end of the conduit is provided with an elongated
- 25 30 discharge screen 34 having the same screening characteristics as the screen 33. The screens 31, 32 and 33 are exactly similar in construction with the exception of the screening qualities thereof. Each of these screens consists of an annular tube 35 in communication with cross tubes 36, the annular and cross tubes being provided with openings 37 for delivering a blast of air in the plane in which they are arranged. To
- 35 40 these tubes are secured the screening material, the openings serving to deliver air against this screening material to remove therefrom any coals too large to pass through the screen. Each annular tube 35 is in communication with a source of compressed air 38 through a conduit 39 extending through the wall of the conduit 30, the conduit 39 having arranged therein a valve 40 and being arranged so that it may
- 45 50 be rotated to vary the angle of the screening device within the pipe after the manner of a damper. These screening devices will normally be arranged so that they entirely obstruct passage of all except certain sizes of material. In order to insure sealing about the edges of the screening element a gasket 41 is preferably arranged in the conduit 30 for this purpose.
- 55 Paralleling the conduit 30 which inclines upwardly from the point of its engagement with the rear end 12 of the drum is a return conduit 42, which conduit 42 is connected with the conduit 30 by a branch pipe 43 entering the conduit 30 adjacent each of the
- 60 65 screening devices 31, 32 and 33 and at that

side of the screening device next adjacent the drum 10. This return pipe 42 communicates with the end 12 of the drum and is provided with a valve 44 which is normally held closed by the pressure of air within the drum but which will open under the pressure of returning coal to permit this returning coal to enter the drum.

In the operation of the device the coal to be pulverized is placed in the hopper and fed into the drum 10 in the manner described, within the drum 10 it is spread in a thin layer by the scrapers 22 and is crushed between rollers 21 and the inner surface of the drum 10. It is pointed out that the mountings of these rollers being pivoted to the arms 19 will permit these rollers to move outwardly under centrifugal force so that a crushing action will be given by the rollers which is proportional to their speed. The device is preferably operated at a high speed and at such speed these rollers will exert great crushing force and furthermore the scraper flanges will tend to throw the coal about to disturb the interior of the drum so that in the air within the drum will at all times be suspended very finely powdered coal. This air is forced by the blast from the blower 29 through the discharge pipe 30 where the coal is screened and finally delivered through the screen 34. Particles which are too large will be checked by the screening devices 31, 32 and 33 and returned to the drum for further pulverization. In event of any of the screens becoming clogged they may be cleaned by operating the valve 40 associated therewith to blow the coal from the screen. In event this proves insufficient the device may be run for a short period while empty, the screens having first been positioned at right angles to their normal position so that they exercise no checking effect upon material passing therethrough. The blast of air passing over the screens will clean the screens and deliver the material removed therefrom to the screen 34 where it will be collected. The screen 34 is preferably made so that it is readily removable for this reason. From the foregoing it will be seen that by the use of a device constructed in accordance with my invention continuous operation of pulverization can be carried on and the delivery of but a single grade of pulverized material guaranteed. It will furthermore be obvious that the structure hereinbefore set forth is capable of a considerable range of change and modification without in any manner departing from the spirit of my invention and I accordingly do not limit myself to such specific structure except as hereinafter claimed.

I claim:-

1. A screening device for material pulverizers having pneumatic means for discharging

- ing pulverized material from the pulverizer including an upwardly inclining conduit, screens arranged within said conduit, means for delivering a blast of air to said screens 5 to remove collected material therefrom, a second conduit substantially paralleling the first named conduit, a connection between said conduits adjacent each of said screens and at that side thereof next adjacent the 10 pulverizing apparatus, the last named conduit communicating at its lower end with said pulverizing apparatus.
2. A screening device for material pulverizers having pneumatic means for discharging pulverized material from the pulverizer including an upwardly inclining conduit, screens arranged within said conduit, means for delivering a blast of air to said screens to remove collected material 15 therefrom, a second conduit substantially paralleling the first named conduit, a connection between said conduits adjacent each of said screens and at that side thereof next adjacent the pulverizing apparatus, the last named conduit communicating at its lower end with said pulverizing apparatus and being provided at the point of communication with a valve opening toward the pulverizing apparatus.
- 30 3. A screening device for material pulverizers having pneumatic means for discharging pulverized material from the pulverizer including an upwardly inclining conduit, screens arranged within said conduit, means for delivering a blast of air to said screens to remove collected material 35 therefrom, a second conduit substantially paralleling the first named conduit, a connection between said conduits adjacent each
- of said screens and at that side thereof next 40 adjacent the pulverizing apparatus, the last named conduit communicating at its lower end with said pulverizing apparatus, each of said screens being rotatable within the conduit, the discharge end of the conduit in 45 which said screens are arranged being provided with a further screening device.
4. In a screening device for the purpose described, a conduit, a plurality of screening devices within said conduit, each comprising a hollow annular pipe with diametrically hollow branches connecting or extending thereacross and a screen secured to said annular pipe, said annular pipe and said branches having openings formed therein 50 directed toward said screen, and a pipe extending through the conduit and communicating with the annular pipe having a valve therein and in communication with a source of air under pressure.
5. In a screening device for the purpose described, a conduit, a plurality of screening devices within said conduit, each comprising a hollow annular pipe with diametrically hollow branches connecting or extending 55 thereacross and a screen secured to said annular pipe, said annular pipe and said branches having openings formed therein directed toward said screen, and a pipe extending through the conduit and communicating with the annular pipe having a valve therein and in communication with a source of air under pressure, the last named pipe constituting a pivot and means for rotating 60 said annular pipe and screen carried thereby.
- In testimony whereof I hereunto affix my signature.

JACOB B. PERKINS.
